KILN RETORT STRUCTURE

Robert Sayre Kent, Brooklyn, N. Y.

Application November 9, 1934, Serial No. 752,277

3 Claims. (Cl. 202—116)

This invention relates to improvements in kilns for drying pulverulent material and especially for drying and revivifying char for use in filtering processes in connection with sugar refining; and 5 the invention has reference, more particularly, to a novel retort structure for such kilns.

This invention has for its principal object to provide a novel self-ventilating retort structure for char kilns which operates with higher efficiency 10 and more rapidly at the temperatures ordinarily heretofore employed (approximately 1000 degrees F.), or with equal efficiency but less rapidly at lower temperatures than heretofore customarily used, by virtue of the fact that the vapors and 15 products of distillation are quickly vented, while in a highly heated state, directly from the retort interiors into the combustion chamber of the kiln without opportunity to contact with the incoming cold stream of char.

20 The invention has for a further object to provide a novel self-ventilating retort structure of multiple pipe form whereby a large increase of heating surface area contactable by the char is provided as compared with the available area of the old cast iron single pipe retorts, while nevertheless occupying no more space than required for said old single pipe retorts, novel vent means being provided in connection with each individual pipe.

25 Another object of this invention is to provide a multiple pipe retort wherein the pipes are preferably of drawn chrome-steel alloy, thus greatly reducing the weight of the retort while at the same time increasing the heat transfer efficiency thereof, in combination with novel means for mounting the multiple retort pipes subject to easy and comparatively quick removal for the purpose of adjusting the same in the kiln to correct warpage, or for replacement when the useful 30 life of the same is ended; the mounting arrangement including novel means whereby each retort pipe is self-ventilating.

35 Other objects of this invention, not at this time more particularly enumerated, will be understood 40 from the following detailed description of the same.

45 Illustrative embodiments of the invention are shown in the accompanying drawings, in which:—

50 Fig. 1 is in part a front elevation and in part a vertical cross section of a kiln equipped with the novel retort structure according to this invention, one of the multiple pipe retorts being shown in elevation and one in vertical section; 55 Fig. 2 is a detail horizontal section, on an en-

larged scale, taken on line 2—2 in Fig. 1; Fig. 3 is another detail horizontal section, also on an enlarged scale, taken on line 3—3 in Fig. 1.

Fig. 4 is an enlarged view similar to that of Fig. 1 but showing the method of handling the 5 retort structures for shifting or replacement.

Fig. 5 is an enlarged elevational view of the top header of the novel multiple pipe retort; and Fig. 6 is an enlarged elevational view of the bottom header of the same.

Fig. 7 is a fragmentary view in part elevation and in part section of a somewhat modified form of the multiple pipe retort structure; and Fig. 8 is a horizontal section, taken on line 8—8 in said Fig. 7.

10 Similar characters of reference are employed in the above described views, to indicate corresponding parts.

Referring to the drawings, the reference character 1 indicates the kiln which is usually constructed of brick. Located within the upper central portion of the kiln is a combustion chamber 2 enclosed by the side walls 3, top arch 4 and floor wall 5. Located beneath the floor wall 5 are air boxes 6 which communicate with the combustion chamber through said floor wall 5, so that adequate air to support the combustion of fuel within said combustion chamber is delivered to the latter. Located within the kiln between the outer walls thereof and said combustion 20 chamber side walls 3 are vertical retort chambers 7, through which the burning gases issuing from the combustion chamber 2 are caused to pass, thus constituting the same continuations 25 of the combustion chamber 2.

30 Mounted in the floor 8 of the kiln, so as to be rigidly and firmly supported thereby within the lower ends of the retort chambers 7, are retort footing members 9 having upstanding peripheral walls 10 bounding seating cavities or sockets 11. 35 Projecting from the underside of each footing member 9 are a plurality of laterally spaced tubular discharge spouts 12, the passages 13 of which communicate with the interior of the seating cavity or socket 11. Connected with and extending downwardly from said spouts 12 are cooler pipes 42 into and through which the material treated in the retorts is discharged.

40 The upper end of the retort chamber 7 is provided with a suitably supported cover plate 14 having dependent passage or hatchway forming members 15 for communication with the retort members per se. Arranged above each series or 45 gang of retort members, which extend through the retort chambers 7 as will subsequently appear,

are feed hoppers 16 leading from the bin 17 into which the material to be treated in the retorts is supplied, so as to flow therefrom by gravity downwardly through the retort members.

The retort members are arranged in gangs extending downwardly and vertically through the retort chambers 7 of the kiln. According to the present invention the said retort members involve a novel form and construction to be now set forth, a detail description of one of which will suffice for all. Each retort comprises a set of pipes 18 of drawn steel or other suitable metal or material, preferably three in number, arranged side by side in laterally spaced apart relation to extend vertically through a retort chamber 7 when in place. The pipes 18 making up a retort forming set thereof are maintained in their grouped relation at their lower ends by means of a bottom header 19. This bottom header is provided in its upper portion with spaced sockets 20 to receive the lower ends of said retort pipes 18. Opening through the bottom wall 21 of the header 19 are discharge openings 22 axially aligned with the bores of said retort pipes 18, said openings 22 being of less diameter than the diameter of the pipe receiving sockets 20, thereby providing annular supporting shoulders 23 upon which the lower ends of said pipes 18 are engaged. On its under side, said bottom header 19 is provided with a plurality of spacer lugs 24 dependent therefrom and preferably arranged in radial relation to the vertical axes of the sockets 20 and the openings 22 so as to form outwardly extending lateral vent channels or spaces 25 between the bottom of the header 19 and the floor of the seating cavity or socket 11 of the footing member 9. The external dimensions of the bottom header 19 are somewhat less than the internal dimensions of the walls 10 of the footing member 9 which bound the seating cavity or socket 11 of the latter, thus providing an upwardly extending vertical vent space 26 providing communication between the aforesaid lateral vent channels or spaces 25 and the interior of the retort chamber 7 in which the retort member is located.

In installations wherein it is not desired to provide the above-described means providing for ventilation communicating with the lower ends of said retort pipes 18, the bottom header 19 may be suitably sealed into the footing members 9, or any other means may be provided for sealing the lower ends of the retort pipes against communication with the interior of the retort chamber 7 of the kiln.

The pipes 18 making up a retort forming set thereof are maintained in their grouped relation at their upper ends by means of a top header 27. In one form thereof this top header is provided with a bottom wall 28 from which depend tubular necks 29, the passages of which communicate with the interior passage 30 of said top header. The external diameters of said necks 29 are somewhat smaller than the internal diameters of the bores of said retort pipes 18, so that said necks enter the upper ends of the latter when the top header is operatively assembled therewith, thereby forming a loose connection providing vertical vent spaces 31. On its under side, said top header is provided with a plurality of spacer lugs 32 dependent therefrom and arranged in radial relation to and extension from said necks 29 so as to form outwardly extending lateral vent channels or spaces 33 therebe-

tween. The upper ends of the retort pipes 18 abut said spacer lugs 32, and consequently the vent spaces 31 leading from said pipe interiors communicate with said lateral vent channels or spaces 33 and through these with the interior 5 of the retort chamber 7. At its upper end portion, the top header is provided with a laterally enlarged coupling portion 34 to receive the hatchway forming members 15 of the retort chamber cover plate 14. Intermediate its ends, 10 said top header is provided with an external laterally extending flange or shoulder 35 which is disposed, when the top headers of the retorts are in place, in the plane of shoulders 36 with which the side walls of the retort chamber 7 is provided. 15 Said shoulders 35—36 serve as supporting means for sealing plugs 37 of fire clay or brick, whereby the upper ends of the retorts are sealed with- 20 in the retort chamber 7.

The arrangement for mounting the multiple pipe retort, as thus above described, is such that the entire structure including the top header 27 is supported by the footing of the bottom header 19 in the footing members 9. This arrangement is satisfactory as a whole, but in some cases it 25 is desirable to so mount the retort that the top header 27 is supported independently of the retort pipes 18, whereby play may be allowed between the top header 27 and the upper ends of 30 said retort pipes so that the latter are free for 35 movement under longitudinal stresses due to expansion and contraction thereof. A mounting arrangement suitable for obtaining the latter results is shown in Fig. 7, wherein a carrying plate 43 is bridged across the upper end of the retort chamber 7, being supported on the wall shoulders 36. This carrying plate 43 is provided with openings 44 through which the lower end of the top header 27 is passed, and the top header is provided with an external annular hanger flange 40 45 to engage the carrying plate 43, whereby the top header is independently supported. With the top header 27 thus independently hung or supported, the upper ends of the retort pipes 18 may be so engaged on the necks 29 so as to be capable 45 of sliding play thereon, which play will permit free movement of the pipes under stresses of longitudinal expansion and contraction thereof.

In Figs. 7 and 8 there is also shown a modified form of retort pipe engaging neck 29, the modification consisting in providing the same with circumferentially spaced externally projecting vertical ribs 46, which, when the ends of the retort pipes 18 are engaged over the necks 29, 50 function to space the pipe walls outwardly from the neck walls, thereby maintaining the vertical vent spaces 31 uniformly concentric to the necks 29.

When the retort members are in place within 60 the kiln as above described, the products or gases of combustion generated within the combustion chamber 2 pass into the upper ends of the retort chamber 7 through entrance ports 38 provided in the side walls 3 of said combustion 65 chamber. The hot gases thus delivered into the retort chamber 7 circulate around the pipes 18 of the retort members, and thence flow downwardly for escape through discharge ports 39 leading to the furnace flues 40, and thence to 70 the stack conduit 41, all as indicated by the direction arrows applied in Fig. 1 of the drawings.

Char or bone-black, or other material to be treated, is supplied to the bin 17, from whence it flows by gravity through the feed hoppers 16 and 75

hatchway forming members 15 downwardly through the top header 27 into and through the retort pipes 18 for final discharge from the latter, after treatment, through the cooler pipes 42. 5 Inasmuch as the retort members each comprise a group of spaced drawn steel pipes 18, as compared with the common single cast iron pipe retort, a much higher heat transfer efficiency is obtained; first, by reason of a greater area of pipe 10 surface externally exposed to contact by the hot gases of combustion circulated through the retort chambers 7 and around the retort members as well as a greater area of pipe surface internally exposed to contact by the char gravitating through 15 the retort pipes, and, second, by reason of the higher conductivity of the relatively thin walls of such steel retort pipes. In the preferred form of three pipe retort member, as herein shown and described, the effective surface area of the retort members is increased from one-third to one-half more than that furnished by the old single pipe 20 retorts. As a result of this the kilns may be satisfactorily operated at the same rate of material flow as employed in the old single pipe retorts, but at a lower temperature than required for the latter, or, conversely, the same temperatures heretofore used with the single pipe retorts may be employed, but with an increased rate of material 25 flow through the retort members. Another advantage of the multiple pipe retort according to this invention lies in the fact that the retort members are of considerably less weight, and consequently can be handled with less labor and difficulty when replacements, repairs or adjustments 30 are required.

While the above mentioned advantages involved in the use of thin walled multiple pipe retorts are desirable, such advantages are somewhat off-set if not altogether lost in the absence of satisfactory means for ventilating the individual pipes. 40 So far as I am aware no satisfactory means for such purpose has heretofore been available, and consequently it is an important object of this invention to provide a construction whereby ventilation of the individual retort pipes may be attained to the end that the products of distillation generated by the treatment of material, such e. g. as char, may be quickly and efficiently removed, while in a highly heated state, from the interior 45 of the retort pipes and away from possible contact with the incoming char stream; for if passed up through the comparatively cold stream of incoming char, the vapors constituting these distillation products are likely to be condensed and absorbed by the incoming char, thereby increasing the load of impurities carried by the latter and consequently rendering the efficient revivification 50 of the char more difficult.

By reason of the construction and arrangement 60 of the novel header means provided by this invention for maintaining the retort pipe sets in operative grouped arrangement, the desired functional advantages are provided whereby each retort pipe is rendered self-ventilating. When, under the application of heat to the char or other material treated in the retort pipes, the liberated vapors and gases constituting the products of distillation are released, the same are easily and quickly driven off without impeding the flow of the material. This is due to the provision of the venting spaces and channels formed between the ends of the retort pipes and either one or both of the header members as above described. The 65 liberated vapors and gases readily escape from

both ends of the retort pipes through these venting spaces and channels into the retort chambers 7 to be carried off by the kiln draft circulation; the novel arrangement being such that the venting is effectively established without sacrifice of 5 the secure maintenance and holding of the retort pipes in their desired spaced and grouped relation.

Another advantage of the novel multiple pipe retort structure lies in the ease with which the same may be handled for replacement, adjustment or repair. For example, in the operation of the kiln, the steady flow of heat against the external surfaces of the retort pipes, tends in time to somewhat warp the same, ordinarily in the direction toward the incoming heat. In such case, 10 it is a comparatively easy matter to open up the top of the kiln and by means of a line or grapple (as shown in Fig. 4) to engage the bottom header and thereupon lift out the retort member, so that the same may be turned and replaced in such 15 position that application of incoming heat will tend to reversely warp the pipes 18 back to initial condition. Owing to the fact that the connections between the retort pipes and the headers form relatively loose joints, it will be obvious that, 20 when the retort is lifted out of the retort chamber 7, the pipes may be easily and quickly either individually turned relative to or entirely dismounted from the headers and replaced by new 25 pipes when such replacement is desirable. 30

I am aware that various changes may be made in the construction of the retort members as above described and as illustrated in the drawings, without departing from the scope of and while still retaining the general principles of this invention. Hence, I do not limit my invention to the exact arrangements and combinations of the devices and parts as described in the foregoing specification, nor do I confine myself to the exact details of the construction of the various parts as 40 illustrated in the accompanying drawings. 35

I claim:—

1. A retort member for kilns having a highly heated retort chamber, comprising a plurality of pipes disposed in parallel vertically extending and 45 laterally spaced relation within said retort chamber, a bottom header to engage and hold the lower ends of said pipes, said bottom header having discharge openings with which the pipes communicate, and a top header having an upwardly open 50 main passage and a lower end wall, tubular necks depending from said lower end wall and communicating with the main passage of said top header, said necks engaging loosely in the upper ends of said pipes, and spacer lugs projecting from the underside of said lower end wall radial to said necks to space the pipe ends from said end wall thereby providing vent spaces opening directly 55 into the heated interior of said retort chamber in communication with the interiors of said pipes. 60

2. In a kiln of the class described having a combustion chamber, retort means comprising a plurality of vertically disposed laterally spaced pipes extending in grouped relation through the combustion chamber between the top and bottom 65 thereof, a bottom header for each pipe group footed in the bottom of said combustion chamber to which the lower ends of said pipes are engaged, a top header for each pipe group sealed in the top of said combustion chamber, each top header having means, providing a char receiving passage externally of said combustion chamber and a lower end wall therefor, tubular necks depending from said lower end wall and communicating with 70 75

said char receiving passage, said necks loosely engaging in the upper ends of said pipes, and means to space said pipe ends relative to said end wall and necks to form escape passages for vapors and products of distillation leading from the pipe interiors directly into the combustion chamber.

3. In a kiln of the class described having a combustion chamber, retort means comprising a plurality of vertically disposed laterally spaced 10 pipes extending in grouped relation through the combustion chamber between the top and bottom thereof, a top header for each pipe group sealed in the top of said combustion chamber, each top header having means providing a char receiving 15 passage externally of said combustion chamber and a lower end wall therefor, tubular necks depending from said lower end wall and communi-

cating with said char receiving passage, said necks loosely engaging in the upper ends of said pipes, means to space said pipe ends relative to said end wall and necks to form escape passages for vapors and products of distillation leading from the pipe interiors directly into the combustion chamber, a bottom header for each pipe group having sockets to receive the lower ends of said pipes and discharge openings leading from the bottoms of said sockets, a footing member for each bottom header 10 fixed in the bottom of said combustion chamber, and means to space the bottom header relative to the footing member to form additional escape passages for vapors and products of distillation also leading from the pipe interiors directly into 15 the combustion chamber.

ROBERT SAYRE KENT.
